[57] **CLAIM**

The ornamental design for a radio channel programming comb, as shown and described.

DESCRIPTION

FIG. 1 is a front elevational view of a radio channel programming comb showing our new design.

FIG. 2 is a bottom plan view thereof.

FIG. 3 is a top plan view.

FIG. 4 is a side view thereof as viewed from the left in FIG. 1.

FIG. 5 is a side view thereof as viewed from the right in FIG. 1.

The rear elevational view thereof is a mirror image of FIG. 1 and is therefore not shown.
